CEILING SUSPENSION CLASP HOOK

Filed Aug. 25, 1949

UNITED STATES PATENT OFFICE

2,586,327

CEILING SUSPENSION CLASP HOOK

William J. Haertel, Oak Park, Ill.

Application August 25, 1949, Serial No. 112,287

1 Claim. (Cl. 24—84)

1 This invention relates to ceiling suspension means particularly useful with pre-formed paneling such as gypsum wall board or other panels which may present a surface for the finished ceiling more particularly in present day concrete building construction.

Among other objects, the invention aims to provide improved and simplified ceiling suspension means that readily and effectively secures the paneling to the rails commonly suspended from the concrete of the usual rough ceiling, the expedients here contemplated avoiding the use of tools, nails or extraneous fastening devices, and effecting economy of labor and material while contributing to a structure which may have desirable insulation and sound absorption properties.

In an important aspect, the invention includes hanger clips which are spring locked to the ceiling rails and which have spaced apart flanges for directly engaging the paneling as well as supporting panel support runners, the runners cooperating to maintain the clips in position on the paneling.

These and other objects of the invention will be apparent from the following description, taken together with the accompanying drawings, of an illustrative embodiment of the invention, and in which drawings—

Figure 1 is a plan view of ceiling suspension means following the present invention, looking thereat from above and just below the usual concrete ceiling;

Figure 2 is a section taken on the line 2—2 of Fig. 1.

Figure 3 is a cross-section taken on the line 3—3 of Fig. 1 and here showing a part of the concrete ceiling;

Figure 4 is an enlarged partial perspective view, showing suspension means embodying the present invention;

Figure 5 is a reversed view of the hanger clip embodying one aspect of the invention; and

Figure 6 is an assembly step view indicating the initial placing of a hanger clip on a rail.

Referring in detail to the illustrative construction shown in the drawings, the numeral 11 (Fig. 3) represents the usual concrete ceiling that may have embedded therein, at intervals, rail supporting fastenings such as, at 12, pairs of wires 13 to support the metal rails 14 which in well known practice may extend for full length across the ceiling 11 uniformly spaced therebelow and suspended therefrom by means of the wires 13. Each pair of wires may be twisted together

as at 15 to carry the rail. As here shown, the rails 14 are of channel formation and disposed with their channel facing laterally.

In accordance with the present invention hanger clips 16, one of which is shown separately in perspective in Fig. 5, are readily assembled with the rails 14 by being manually hung thereover at appropriate intervals such as presently indicated. Each hanger clip 16, as here shown, is advantageously struck out of sheet metal and comprises an upright leg 17 and an overhanging arm 18 which are coplanar in that they are formed by striking out the parts therefor from flat sheet metal stock and thus disposing the leg and arm in predetermined angular relation. Advantageously, the arm 18 may be continued downwardly at its outer end for a short distance as a hook element 19.

At its lower end, the leg 17 of the clip 16 is integral with the clip base 20 which is extended in the direction of the arm 18 and is here shown bent and reverse bent upon itself, in a direction at right angles to the plane of the arm and leg, to provide a pair of spaced apart overlapping flanges 21 and 22 with an upright bight portion 23 therebetween. The lower flange 22 is preferably extended out from the plane of the arm and leg portions on each side thereof so that the latter desirably occur in a somewhat median plane extending longitudinally of the lower flange 22.

Following the present invention, the clip base 20 at its end adjacent the outer end of the arm 18 has struck out integrally therewith, and all 35 initially in the flat as previously referred to, a somewhat triangular upwardly extending tongue 24 which after the clip is formed as described is bent out of the plane of the leg 17 and the arm 18, as shown in the drawings, to provide a spring 40 tongue which acts as a yieldable closure or lock for the space 25 within the confines of the clip parts. This space 25 is conveniently substantially just slightly larger than the cross sectional dimensions of one of the rails 14.

45 When now, as previously mentioned, the clip 16 is hung over the rail 14, it may be first engaged with the rail as shown in Fig. 6, in a tilted position with respect to the rail, so that the upper flange of the rail is received within the space 50 25 and with the hook 19 engaged thereover. At this time the lower flange of the rail 14 will rest on the inclined face of the yielding tongue 24. By pushing the clip farther onto the rail, with a rotative motion (Fig. 6) the tongue 24 is resiliently depressed and the rail disposed within the

confines of the space 25, whereupon the tongue 24 springs upwardly to lock the clip on the rail with the clip in suitable upright position as shown in Figs. 1 to 4 inclusive. The outer edge of the tongue 24 is desirably slanted as at 26 providing a formation in the nature of a cam which facilitates this action when the tongue first engages the rail.

Still further in accordance with the present invention, longitudinally extending panel support runner members 27 are assembled with the clips 16, these runner members being desirably of H-shape in cross-section as shown in the drawings thus providing a pair of oppositely facing grooves 28 and 29. The runners extend cross-wise of the rails 14 and may similarly extend the entire distance of the room. When a runner 27 is assembled with a plurality of the clips 16 it receives the flanges 21 and 22 and bight portion 23 of the clip base within one of the grooves, such as 28 of the runner.

The wallboard or the like 30 is conveniently of elongated flat panel form, the panels having their longer dimension extending similarly to the runners 27 and transversely to the rails. As here contemplated, the longer margins of the panels 30 are received both in the bight 23 of a clip 16 and in the groove such as 28 of the runner 27, by a snug gripping fit. The runners 27 thus serve both to directly support a panel 30 and at the same time to hold the clip onto the panel, the clip in turn supporting itself, the runner member, and the paneling, on the rail 14.

Since the runners 27 provide the oppositely laterally facing grooves 28 and 29, the adjacent margin of an adjacent panel 30 may be received in the runner groove 29 and thus be securely supported and held in place without a clip bight 23 engaging this last mentioned margin of a panel. Thus the clips need only engage one edge of the joining panels while securely supporting both edges as shown.

The runner members 27 may be economically formed from two initially flat strips each bent to channel shape and with their bight spot-welded back to back as at 31.

Since the panels are commonly not as long as the runners and are preferably staggered or in break-joint arrangement, adjacent ends of adjoining panels may have disposed therebetween short runners 32 similar to the runners 27 but extending transversely to the runners 27 and terminating short of a pair of adjacent runners.

So constructed and arranged the paneling is spaced below the rails allowing sufficient room for the twisted ends 15 of the wires 13 and also providing a desirable air space between the paneling and the main ceiling 11.

It will be understood that any desired finishing material may be applied to the undersurface of the paneling, forming no part of the present invention but for producing a decorative ceiling.

The invention is not intended to be limited to details of construction shown for purposes of exemplification. Furthermore it may not be essential that all features of the invention be used conjointly at all times, since various combinations or subcombinations may be advantageously employed. Such changes may be made as fall within the scope of the appended claim without departing from the invention.

See also my copending application, S. N. 112,-288 filed concurrently herewith.

The invention having been described, what is here claimed is:

A sheet metal ceiling suspension clip embodying spring-tongue locking means, comprising, a C-shape part including a base portion, an upright leg portion, an overhanging arm portion, and a hook portion depending from the outer end of said arm, said portions being all coplanar, a triangular shape spring-tongue integral with said base and projecting upwardly therefrom obliquely away from the plane of said C-shape part, said tongue having an outer edge extending obliquely in the plane of said tongue from said base to the apex of the tongue, the apex being substantially in the transverse vertical plane through the inner edge of said hook portion, whereby the tongue outer edge provides a cam for effecting a resilient depression of the tongue when the clip is pressed onto a ceiling beam member by movement in a direction normal to the latter to receive the beam member in the C-shape part in locking engagement, the base of the C-shape part being extended at its lower edge laterally in both directions from the plane thereof to form a pair of overlapping flanges to receive a ceiling panel element.
